C. H. HAPGOOD
APPARATUS FOR DISCHARGING UNCONTAMINATED WATER FROM THE BILGE
OR BALLAST TANKS
Filed Jan. 31, 1924

UNITED STATES PATENT OFFICE.

CYRUS HOWARD HAPGOOD, OF NUTLEY, NEW JERSEY, ASSIGNOR TO THE DE LAVAL
SEPARATOR COMPANY, OF NEW YORK, N. Y., A CORPORATION OF NEW JERSEY.APPARATUS FOR DISCHARGING UNCONTAMINATED WATER FROM THE BILGE OR
BALLAST TANKS.

Application filed January 31, 1924. Serial No. 689,708.

To all whom it may concern:

Be it known that I, CYRUS HOWARD HAPGOOD, a citizen of the United States, residing at Nutley, county of Essex, and State of New Jersey, have invented a new and useful Improvement in Apparatus for Discharging Uncontaminated Water from the Bilge or Ballast Tanks, of which the following is a full, clear, and exact description, reference being had to the accompanying drawings, which form a part of this specification.

In an application filed by me September 12, 1923, Serial No. 662,364, Patent No. 1,481,901, for process and apparatus for discharging uncontaminated water from bilge or ballast tanks, I set forth a process wherein the liquid from the tank is pumped against a constant head and wherein the pump pressure itself tends to shut off the flow of liquid toward the discharge. Normally this pump pressure is opposed by a force sufficiently great to maintain the flow during discharge of water. When, however, due to passage of oil into the pipe, the liquid becomes more viscous, the pump pressure increases and overcomes the opposing force and shuts off flow of liquid. In said patent I also set forth an apparatus adapted to carry out such process, the same comprising a pipe line leading from the tank and arranged to provide a fixed head, a control valve on the pipe line, a pump between the tank and the control valve, and means, such as a spring-pressed diaphragm, that holds the valve open against pump pressure during outflow of water but that yields to the increased pump pressure produced when oil starts to outflow, and closes the valve, thereby arresting further discharge of liquid.

This process and apparatus are in every sense operative, but in the practical development of the invention I have made certain improvements whereby new and useful results are obtained and whereby the process and apparatus are better adapted to respond to the requirements of regular commercial use.

In said apparatus, after oil starts to flow from the tank, most of the oil is shunted through a relief valve; but a small percentage of oil will get beyond the control valve before the latter closes. In said patent pro-

vision is made (namely: a branch pipe and a manually operable junction valve) whereby, if the control valve be held open, the emulsion of water and oil in the pipe beyond the control valve may be subsequently pumped back to a ballast tank or to the bilge or to a receptacle for subsequent conveyance to a centrifugal separator, thereby avoiding the passage of any oil to the discharge. It is clear that if diversion of all the oil entering the pipe line could be effected automatically, without manual operation of these valves or either of them, it would be of decided advantage and utility. The present invention is adapted to effect this result.

It is also clear that in the patented apparatus, an accurate adjustment of the control valve mechanism is required, so that only a slight increase of viscosity and therefore only a slight increase in pump pressure may insure the closure of the valve. Bearing in mind that, when oil starts to flow from the tank, its proportion to water is very slight, the proportion increasing as the flow continues, it is clear that if the control valve mechanism is not adjusted to respond to a slight increase of pump pressure, considerable oil may go to the discharge before the control valve closes. It is evident that if the construction could be modified so as to dispense with the necessity of a fine or delicate adjustment of the control valve mechanism, so that if the control valve should fail to close until after a considerable proportion of oil enters the pipe, yet no oil would pass to the discharge, a very useful result, from a commercial standpoint, would be obtained. The present invention accomplishes this desirable result.

In the embodiment of my invention herein set forth, the purposes of my invention are mainly accomplished by locating the control valve at a point relatively distant from the pump and operating the control valve by pump pressure transmitted through a branch pipe line, so that no oil will ever pass the control valve even though considerable oil may pass the pump and build up a substantially increased pressure before closure of the control valve.

Another advantage of my improvement is that there is no necessity to flush out the discharge pipe beyond the control valve at

any time; oil never flowing into this part of the pipe. On the other hand, at the beginning of each ballast tank-exhausting operation, such part of the pipe as contains oil 5 may be thoroughly flushed out before allowing water to pass to the discharge.

In the drawings, which show a preferred embodiment of my invention:

Fig. 1 is a sectional elevation, somewhat 10 diagrammatic, of a preferred embodiment of my invention.

Fig. 2 is a sectional elevation of the control valve, for which may be substituted any standard form of pressure regulator.

15 *a* is the tank for ballast water. It may also represent the bilge. *b* is a pipe line leading therefrom. This pipe extends up to any convenient discharge level and has a downwardly curved end which extends into 20 a vertical conduit *c*, which communicates at its lower end with a vertical conduit *d*; the conduits affording two balanced columns of liquid capable of acting as a separator. In the present invention, however, no necessity 25 exists for providing separating means beyond the pipe discharge. The pipe may discharge directly into the body of water in which the vessel floats. If the separator *c*—*d* is provided, overflow pipes *e* and *f* are 30 provided from the respective columns *c* and *d*.

In the pipe *b*, preferably relatively close to the tank *a*, is a pump *g* arranged to operate at a constant speed. Between the pump 25 *g* and the discharge end of pipe *b* (preferably nearer the latter than the former) is a control valve *h*. Behind the control valve, but preferably rather close thereto and relatively distant from the pump, is a relief 40 valve *i*. From the relief valve extends a pipe *j* which, like pipe *e*, discharges into a tank *k* having a heating coil *m*. Tank *k* discharges into a centrifugal oil purifier *n*; the water discharge *o* from which is connected to the bilge, while the oil discharge 45 connects with a pipe *p* leading to a lubricating oil receiver and with a pipe *r* leading to a fuel oil receiver; the passage of the oil being governed by a three-way valve *s*.

50 The details of the control valve *h* (which is a well known type of pressure regulator and forms per se no part of my invention) are shown in Fig. 2. The valve casing has a double seat *t* engageable by valve discs *u*. 55 The valve stem extends out through a stuffing box *v* and carries at or near its outer end a diaphragm *w* located in a chamber *x*. A spring *y* tends to hold the valve open.

60 Communicating with the diaphragm chamber *x* is one end of a pipe *z*. The other end of pipe *z* connects with pipe *b* in front of the pump *g*.

The operation of the apparatus described is as follows:

65 By reason of gravity, the oil in tank *a* has

floated to the top. When the pump *g* is first operated, and until the tank is fairly well drained, nothing but water is pumped through pipe *b*, which water is discharged into the separator *c*—*d*, or directly into the harbor water. Spring *y* is so adjusted that as long as the resistance to flow through pipe *b* remains constant, the pump pressure, transmitted through the body of liquid in pipe *z* and acting on diaphragm *w*, is not sufficient to move the valve discs *u* against the force of spring *y* operating to hold them off their seats. As long as nothing but water is pumped through pipe *b*, this resistance to flow remains constant. However, as soon as a measurable proportion of oil begins to come through with the water, there is an increased resistance to flow due to the viscosity of oil exceeding that of water. Hence the pressure against diaphragm *w* increases. Spring *y* may be so adjusted that it will be overcome by the pump pressure when only a very small percentage of oil begins to come through with the water. So fine an adjustment, however, requires the exercise of care and skill. In the present invention, the adjustment may be such that the pump pressure will not overcome the spring until considerable oil has entered the pipe *b*; that is, until a considerable length of pipe *b* contains a weak emulsion of oil with water. While the pipe *b* is thus filling up with this emulsion, the proportion of oil passing through the pump will ordinarily gradually increase. It will thus be understood that the adjustment of spring *y* may be such that it will be overcome either by a slight, or by a rather considerable, increase of pump pressure; so long as the closing of the control valve is insured before any oil reaches the control valve. As soon as the valve discs start to move toward their seats, the throttling effect thus produced rapidly builds up the pressure, insuring a rather rapid, and complete, closure 105 of the valve.

110 As soon as the control valve starts to throttle, relief valve *i* starts to open, and soon all the liquid pumped from tank *a* is passing through pipe *j* into receiving tank *k*. This continues until tank *a* is emptied.

115 The emulsion of oil and water entering receiver *k* is heated and flows into the centrifugal purifier *n*, wherein the oil and water are separated. The water is returned to the bilge. The oil (dependent upon its character and quality) is led either to a lubricating oil tank or a fuel oil tank.

120 When it is again desired to empty a ballast tank or the bilge, as the case may be, pipe *b* is connected (through a valve-controlled manifold *q*) with the tank to be emptied (or with the bilge if it is not already connected therewith), the control valve is held closed, and the emulsion of oil and water in 125 130

the pipe *b* is pumped through relief valve *i* into pipe *j*. As soon as nothing except water is observed to be flowing through pipe *j*, the control valve is opened and will thereafter be held open by spring *y* until oil again passes into pipe *b*. Thus, pipe *b* is thoroughly purged of oil at the start of the operation of emptying a ballast tank or the bilge.

As hereinbefore stated, separator *c-d* may be omitted, as nothing but water will ever pass into it. However, if the separator is provided, and if for any reason any oil in pipe *b* passes the control valve, it will discharge into the separator. Such oil will not flow into column *d* of the separator, but will separate by gravity in column *c* and rise to the top thereof and when a sufficiently thick layer of oil builds up therein, will overflow through pipe *e* into tank *h*. There is no novelty in this separator per se.

While the invention is especially applicable to the purpose described, it is clear that it is also applicable to any situation requiring the pumping of water out of a tank and the automatic separation out of oil or grease contained in the water.

An example of such a situation is the case of field tanks in the oil fields. In these tanks water settles by gravity, and is removed before delivering the oil, which must conform to standard specifications, to pipe lines. By the use of my system, the water, after settlement, may be pumped out and flow of oil from the tank will be arrested automatically.

The invention is also applicable to a variety of uses other than those above described, of which the following is an example. In the manufacture of tallow, after the bones and scrap have been sufficiently cooked, the contents of the rendering tank consist of undissolved solids at the bottom, stick-water (from which glue is made) in the center and tallow at the top. The lever of the bottom of the tallow is determined by the try-cocks as the stick-water is pumped out to the stick-

water evaporator, and when tallow appears at the lowest try-cock the pump is shut down, the valves in the discharge pipes changed and the tallow, with some water, is pumped to the tallow tank. The water is subsequently drained from the bottom of the tallow tank. By the use of my invention, however, the pumping down of these rendering tanks could be done automatically and without carrying any appreciable quantity of stock-water over with the tallow.

It will, therefore, be understood that I intend to cover all the uses of which the apparatus is capable.

Having now fully described my invention, what I claim and desire to protect by Letters Patent is:

1. In an apparatus of the character described, the combination with a reservoir, a pipe line leading therefrom and extending toward a discharge and providing a fixed head, a pump interposed in the pipe line, a control valve in the pipe line beyond, and relatively distant from, the pump, a branch pipe communicating with the pipe line between the pump and the control valve, and means, responsive to pressure in the branch pipe due to increase of viscosity of the flowing liquid, adapted to close the valve.

2. An apparatus in accordance with claim 1 comprising also a relief valve between the pump and the control valve adapted to open when the flow past the control valve is obstructed, and located at such distance from the pump that substantially all the more viscous liquid passing the pump may be, during the continued operation of the pump, automatically diverted through the relief valve.

In testimony of which invention, I have hereunto set my hand, at New York, on this 28th day of January, 1924.

CYRUS HOWARD HAPGOOD.
